UNITED STATES PATENT OFFICE.

NORMAN P. HARSHBERGER, OF CHICAGO, ILLINOIS, ASSIGNOR TO TEE-LOK SHINGLE COMPANY, OF CHICAGO, ILLINOIS, A CORPORATION OF ILLINOIS.

SHINGLE MACHINE.

Application filed June 9, 1921. Serial No. 476,241.

This invention relates to shingle machines and has for its object the production of an improved machine for cutting out shingles or other articles from strips of material.

Of the accompanying drawings Fig. 1 is an enlarged plan view of a shingle which is to be formed by my machine; Figs. 2 and 3 are respectively a plan and an elevation 10 of a shingle cutting machine, which embodies the features of my invention, certain parts in each view being broken away; Fig. 4 is a section along the line 4—4 of Fig. 2; and Fig. 5 is a plan view of one of the block 15 cutters.

Although I have herein illustrated a particular type of shingle which is to be formed by my machine, yet it is to be understood that any ordinary type or shape of shingle 20 may be formed provided the machine is suitably arranged and adjusted therefor. Also it should be understood that the use of my invention is not necessarily limited to the manufacture of shingles, but may be applied 25 to manufacturing various other articles which are formed similarly to the shingles herein described.

The machine for cutting the shingles 3 is mounted on a frame 4, and, in general it 30 consists of a series of knives 5 which are properly arranged, and are mounted upon supporting blocks 6 which are carried by some suitable form of mechanism for moving the blocks forwardly, such as a chain 35 belt 7 passing over suitable wheels 8. Any suitable driving mechanism may be used to operate the wheels by means of a pulley 9 or other suitable mechanism. Above the blocks, as they are moved forwardly, is 40 mounted a roller 10, and between the roller and the blocks the sheet of the material 11 to be made into shingles is passed, and the cutting is done by the knives 5 mounted on the blocks as the material passes between the 45 roller and the blocks. Each of the blocks is somewhat longer than the strip is wide, and each block is substantially as wide as the individual shingles are long, but the general shape of the blocks is as indicated by 50 Fig. 5 or by the double lines of Fig. 2 which indicate the edges of the blocks. Although it is not material to the present invention, yet this particular type of shingle, and the reasons for the special manner of 55 cutting the same, is specifically set forth in

my copending United States patent application Serial No. 458,439, filed March 18, 1921, and reference may be had to that application for a more complete description of the same. In order to cut the shingles as 60 indicated it will be seen that the shingles along the outer edges of the strip are half a shingle forward of the central shingles, so that the knives for cutting a shingle from each of the four rows of shingles may 65 be confined to one block, but the knives for cutting the outer rows of shingles are further forward than are those for cutting the inner rows. However, obviously, it is necessary to have only one knife for cutting between two adjacent shingles, so that I arrange to have the left hand edge of each block carry the knives for cutting between the adjacent shingles in the same rows.

The blocks are arranged to be transported 75 horizontally with the knives extending upwardly, by means of the chain belt having links 12 to which the blocks are suitably fixed in such a manner as to allow the chains to pass freely around the supporting pulleys. The roller 10, which is rotatively mounted above the blocks, extends substantially the full length of the blocks. This roller is mounted so that the position there- 80 of with relation to the upper position of 85 the knives may be sensitively adjusted in any suitable manner. I prefer to mount the bearings of the roller in the frame 13 and to maintain the roller in the proper position by means of the adjusting screws 14.

In operation it is usually desirable to maintain the roller in such a position that there will be a very slight space between the lower surface thereof and the upper edges of the knives 5. Ordinarily the material 90 used for cutting out the shingles is of such a nature that it is unnecessary to cut entirely through the material, a slight portion being easily broken by the ordinary manipulation of the shingles; but, if necessary, the roller may be arranged so that its surface will actually come in contact with the upper edges of the knives. The knives are composed of thin strips of steel, and hence, with ordinary shingle material, 100 sharpening of the knives is not ordinarily required.

The material from which the singles are made comprises a strip 11 of the width indicated in Fig. 2, and of any suitable 110

length. The strip is fed into the machine between the knives and the roller 10, and as soon as the forward end is passed between the roller and the knives, the knives 5 will, by virtue of the driving mechanism, continuously carry the strip forwardly under the roller so that the entire strip will be properly cut into shingles. It will be seen that, in cutting out the shingles, the strip 10 is cut in two longitudinally along the center. This longitudinal cut may be arranged for by knives on the blocks 6, just as the other cuts are made. But I prefer to make the longitudinal central cut by means of a 15 knife 15 surrounding the central portion of the roller 10.

In order to properly support the blocks any suitable means may be used. I prefer for the purpose the rails 16 and 17. The 20 rails 16 firmly support the blocks as they are passing under the roller 10 and the cutting is taking place; and the rails 17 prevent any undesirable vibrations or other transverse movement of the blocks. Rollers 25 18 may be used to reduce the friction, and they answer the double purpose of carrying the links 12 along the rails and also around the wheels 8. A transverse roller 19 is used to support more firmly the blocks directly 30 under the roller 10; and this provides a suitable support for the central rear portion 20 of the blocks which are not adequately supported by the rollers 18.

Inasmuch as the shingles when cut are 35 pressed by the cutters between the knives it becomes necessary to provide means for removing the shingles from the blocks. Any suitable means may be used for removing the shingles from the blocks, but I prefer 40 for the purpose to provide upon the forward axle 21, wheels 22. Upon these wheels are fixed certain plungers 23 which are arranged to pass through openings 24 cut in the blocks as the blocks reach the forward supporting wheel 8. These plungers press the 45 shingles, or portions thereof, outwardly from the blocks, as the blocks pass around the forward wheel. The shingles are thus all pushed free from the blocks as they pass 50 along the lower portion of the front supporting wheels, and are deposited in a pile from whence they may be conveniently removed in any suitable manner. It will of course be understood that the arrangement 55 of the knives and of the plungers, and the sizes of the supporting wheels 8, with reference to the width of the blocks, the arrangements of the openings through the blocks, and the like, must all be properly designed 60 for cutting out and removing the shingles.

The strip of material 11 is fed into the machine by any suitable means, such as by the roller 25; and flanges 26 on the roller, and flanges 27 on the roller 10, or other suitable guiding means for the strip, are pro-

vided. The direction of movement of the blocks is indicated in Fig. 3 by the arrow. In order to properly adjust the knives and the supporting wheels 8, and to prevent slackening in the link belts, the bearings 28 70 of the axle 21 are slidably mounted in the frame 29, and adjustably positioned therein by means of the bolts 30. It is to be understood, however, that modifications may be made in the details of the mechanism herein described by those skilled in the art, without departing from the spirit of my invention as disclosed by the following claims. 75

I claim as my invention:

1. A machine for cutting shingles from a 80 relatively flat sheet of composition roofing material, said machine comprising a plurality of blocks arranged for movement one in advance of the other, means pivotally connecting one end of each block with the 85 central portion of the following block, means for moving said blocks forwardly, cutting knives projecting from each of said blocks and adapted to cut through the roofing sheet and arranged to conform to the shape of the 90 shingles to be cut, means for forcing the sheet against said knives, and a roller positioned under said supporting means for supporting said blocks.

2. A machine for cutting shingles from a 95 relatively flat strip of composition roofing material, comprising a plurality of connected blocks arranged one in advance of the other, each block carrying cutting knives 100 projecting from the block to cut through the roofing strip and arranged to conform to the shape of the shingles being cut, and a roll for forcing the roofing strip against said knives for cutting shingles from said strip in the movement of the blocks and roll 105 relatively to each other, both sides of said knives being alike.

3. A machine for cutting individual shingles from a relatively flat strip of composition roofing material, comprising a plurality of blocks, dividing knives projecting from the blocks to divide the strip into a plurality of individual shingles, a roll arranged above said blocks for forcing the roofing strip against said knives for dividing the strip into the individual shingles in the movement of said blocks under said roll, and means for moving said blocks, said knives having perpendicular sides and flat cutting edges. 115

4. A machine for cutting shingles from a relatively flat strip of composition roofing material, comprising a plurality of blocks, cutting knives projecting from the blocks to cut through the roofing strip, a roll above 125 said blocks for forcing the roofing strip against said knives for cutting individual shingles from said strip in the movement of said blocks under said roll, means for moving said blocks, rollers fixed to said blocks 130

and means for supporting said rollers while passing under said roll.

5. A machine for cutting individual shingles from a relatively flat strip of composition roofing material, comprising a plurality of connected blocks arranged one in advance of the other, each block carrying cutting knives projecting from the block to cut through the roofing strip and arranged to conform to the shape of the shingles being cut, the knives on each block being arranged to cut a plurality of shingles from the width of the strip with the shingles between those at the sides of the strip joined together, a roll arranged above said block for forcing the roofing strip against said knives in the movement of the blocks under said roll, and a blade on said roll for severing the strip longitudinally between the joined shingles of each block.

6. A machine for cutting individual shingles from a relatively flat strip of composition roofing material, comprising an endless row of connected blocks, each block carrying cutting knives projecting from the block to cut through the roofing strip and arranged to conform to the shape of the shingles being cut, a roll above said blocks for forcing the roofing strip against said knives for cutting individual shingles from said strip as the blocks are moved under said roll, means for moving said row of blocks, and means acting from above the blocks and through slots therein for ejecting the cut shingles therefrom when the shingles are facing downwardly.

7. A machine for cutting shingles from a relatively flat strip of roofing material, comprising an endless row of connected blocks, each block carrying cutting knives projecting outward from the block and arranged to conform to the shape of the shingles being cut, a roll above said blocks for forcing the roofing strip against the knives in the move-

ment of the blocks under said roll, and 45 rollers on the blocks for supporting the blocks as they are moved under said roll.

8. A machine for cutting out articles from strips of material, comprising a frame, blocks mounted on said frame and arranged 50 to move in a substantially straight line for a limited distance, a roller extending across and adjacent to the straight line path of motion of said blocks, knives mounted on said blocks and projecting towards and substantially to the adjacent portions of the periphery of said roller as the blocks pass the point nearest to said roller, means for passing strips of material between said roller and said blocks, a pair of guide rails 60 mounted on said frame adjacent said roller but on the opposite side of said blocks and running parallel with the straight line path of motion of said blocks, and means fixed to each of said blocks, and arranged to coact 65 with said guide rails, to prevent movement of said blocks away from said roller as said strips are being cut by said knives.

9. A machine for cutting shingles from a sheet of roofing material, said machine comprising a supporting frame, an endless chain belt, sprocket wheels carried at the end of said chain for driving said belt, a plurality of blocks forming links in said chain, each of said blocks being pivoted at one end to 70 the adjacent links and being pivoted to the other adjacent links near the central portion of the block, cutting knives projecting 75 outwardly from each of said blocks for cutting through the said sheet and arranged to 80 conform to the shape of the shingles being cut, and means acting from above the blocks for forcing the cut shingle out from between the knives.

In testimony whereof, I hereunto set my 85 hand.

NORMAN P. HARSHBERGER.
